United States Patent Office

Des. 205,667
Patented Sept. 6, 1966

205,667

COMBINED VALET AND CLOTHES HANGER

Harry Ernest Rubens, Gorham Island, Westport, Conn.
(2 Sutton Place S., New York, N.Y. 10022)

Filed Oct. 21, 1965, Ser. No. 87,710

Term of patent 14 years

(Cl. D33—8)

FIG. 1.

FIG. 2

FIG. 1 is a perspective view of a combined valet and clothes hanger showing my new design;

FIG. 2 is an exploded elevational view taken from one side thereof.

I claim:

The ornamental design for a combined valet and clothes hanger, as shown.
